UNITED STATES PATENT OFFICE.

FRANK BURTT, OF KALAMAZOO, MICHIGAN.

CLEANING MACHINE.

Application filed December 31, 1927. Serial No. 243,850.

The main object of this invention is to provide an improved machine for cleaning erasers and the like which is of large capacity and highly efficient.

5 A further object is to provide a machine of this character in which the dust is collected so that it may be easily removed from the machine.

10 Objects pertaining to details and economies of my invention will definitely appear from the description to follow. The invention is defined in the claims.

15 A structure embodying the features of my invention is clearly illustrated in the accompanying drawing, in which:

Fig. 1 is a side elevation of my improved cleaning machine with portions in vertical central section.

20 Fig. 2 is an elevation looking from the left of Fig. 1, a portion of the drum being broken away.

25 Referring to the drawing, the base 1 is of suitable dimensions to support the machine, which is preferably portable. The drum designated generally by the numeral 2 is rotatably supported on the shaft 3 carried by the pedestals 4. The drum comprises a peripheral wall 5 and side walls 6, the side walls having peripheral flanges 7 embracing the 30 peripheral wall 5. The peripheral wall and the side walls are secured to the annular angle iron reinforcing members 8.

35 A plurality of baffle walls 9 are disposed in spaced relation transversely between the side walls and provide a plurality of inwardly opening buckets adapted when the machine is in operation to pick up the erasers, allowing them to fall from an elevated position to jar the dust therefrom. These baffle walls 40 9 are preferably disposed at an angle to the radial plane of the drum, thereby providing buckets having acute angles at one end. The walls 9 are provided at their ends with attaching flanges 10 which are secured to the 45 side walls of the drum.

50 In the acute angles of the buckets I arrange dust collectors 11 which are of scroll cross section and formed of sheet metal. The outer overlapping edge 12 is lapped upon and secured to the inner side of the peripheral wall of the drum. The inner edge 13 of these scroll-shaped collectors is spaced from the outer overlapping portion, thereby providing longitudinal inlet passages or mouths 14 extending transversely across the drum.

55 The drum is rotated in the direction of the arrow in Fig. 1 so that as the drum revolves the erasers are, as stated, picked up by the buckets and allowed to drop, thereby jarring the dust therefrom and the dust is carried 60 into the buckets which, owing to their shape, effectively retain the same.

65 One of the side walls has clean-out openings therein registering with the collectors, the clean-out openings having closures 15. One of the side walls is also provided with a door 16 for the introduction and removal of the articles to be cleaned.

70 The structure illustrated is driven from a motor 17, the driving belt 18 being passed around the periphery of the drum. A belt tightener 19 is provided for the belt.

75 My improved cleaning machine is very efficient and of large capacity, the dust being effectively collected as it is dislodged from the erasers so that it is not pounded or embedded in the erasers by the tumbling thereof within the drum. The structure is also comparatively economical and is very convenient to use.

80 Having thus described my invention what I claim as new and desire to secure by Letters Patent is:

1. In a structure of the class described, the combination of a rotatably mounted drum 85 provided with a plurality of transversely disposed baffle walls projecting inwardly from its peripheral wall, said baffle walls being disposed at an angle to the radial planes of the drum so that they are inclined in the direction of rotation of the drum, dust collectors of scroll cross section disposed in the acute angles formed by said baffle walls with their outer overlapping edges against the peripheral wall, the overlapping portions of the 90 dust collectors being spaced providing longitudinal inlet passages for the collectors, 95 one of the walls of the drum having clean-out openings therein aligned with said collectors.

100 2. In a structure of the class described, the combination of a rotatably mounted drum provided with a plurality of transversely disposed baffle walls projecting inwardly from its peripheral wall, and dust collectors 105 of scroll cross section disposed in front of said baffle walls and the angles formed thereby with their outer overlapping edges against the peripheral wall, the overlapping portions of the collectors being spaced pro- 110

viding longitudinal inlet passages for the collectors.

3. In a structure of the class described, the combination of a rotatably mounted drum provided with a plurality of transversely disposed cross walls projecting inwardly from the peripheral wall and coacting with the walls of the drum to provide a plurality of inwardly opening buckets, and dust collectors arranged in the forwardly facing corners of said buckets transversely across the drum, said dust collectors being of scroll cross section with the outer edge disposed upon the peripheral wall of the drum and the overlapping portions spaced providing inlet openings, one of the side walls of the drum having clean-out openings therein alined with said dust collectors and provided with closures.

4. In a structure of the class described, the combination of a rotatably mounted drum provided with a plurality of baffles, and dust

collectors of scroll cross section arranged in front of said baffles with their outer overlapping edges against the peripheral wall of the drum, the overlapping portions of the collectors being spaced providing longitudinal inlet passages for the collector, one of the walls of the drum having clean-out openings therein alined with said collectors. 25 30

5. In a structure of the class described, the combination of a rotatably mounted drum provided with a plurality of transverse baffles, and a dust collector disposed transversely across the drum in front of one of said baffles, said dust collector being of scroll cross section with the outer edge secured to the peripheral wall of the drum and the overlapping portions spaced providing a longitudinal inlet opening. 35 40

In witness whereof I have hereunto set my hand.

FRANK BURTT.
